DESIGN FOR A SETTING FOR A GEM OR SIMILAR ARTICLE

Maurice J. Schless, New York, N. Y., assignor to Jacob J. Fischer, doing business as American
Setting Company, Newark, N. J.

Application November 2, 1944, Serial No. 116,100

Term of patent 14 years

(Cl. D45—1)

To all whom it may concern:

Be it known that I, Maurice J. Schless, a citizen of the United States and a resident of the Borough of Manhattan, county, city, and State of New York, have invented a new, original, and ornamental Design for a Setting for a Gem or Similar Article, of which the following is a specification, reference being had to the accompanying drawing, forming a part thereof, in which

I claim:

The ornamental design for a setting for a gem or similar article, as shown.

MAURICE J. SCHLESS.
